CLAIM

The ornamental design for a fuel cap, as shown and described.

DESCRIPTION

FIG. 1 is a perspective view of a fuel cap, according to the present invention;

FIG. 2 is a front elevational view, the rear elevational view being a mirror image thereof;

FIG. 3 is a top plan view thereof; and,

FIG. 4 is a side elevational view, the opposite side being a mirror image thereof.

The broken line showing of the threaded portion of a fuel cap and the retaining member shown in FIGS. 1, 2 & 4 are for illustrative purposes only and do not form any part of the claimed design.
